UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed December 4, 1923. Serial No. 678,415.

To all whom it may concern:

Be it known that I, EDWARD S. STIMPSON, a citizen of the United States, residing at Hopedale, in the county of Worcester 5 and State of Massachusetts, have invented an Improvement in Feeler Mechanisms for Looms, of which the following description, in connection with the accompanying drawings, is a specification, like characters on 10 the drawings representing like parts.

This invention relates to feeler mechanisms for looms, and more particularly to feeler mechanisms of the intermittent type.

In feeler mechanisms of the intermittent 15 type, the feeler is held in its inoperative or frontward position for periods of time and at intervals is permitted to return to its rearward or feeling position to detect the condition of filling in the shuttle and, on 20 substantial exhaustion thereof, to effect replenishment. Where the filling is of tender character, such as fine yarn or silk, the importance of holding the feeler from recurrent contact with the filling on successive 25 detecting beats becomes apparent.

In some characters of yarn, silk, for instance, the recurring contact of the feeler with the filling is often observable in the 30 finished product because the yarn becomes more or less flattened at the feeler contacting point.

One of the objects of the present invention is to provide a feeler mechanism of the 35 intermittent type wherein the feeler may not only be held in its frontward or inactive position for periods of time but may be actually moved frontward sufficiently to prevent any contact of the end of the feeler with the filling on subsequent detecting 40 beats and until the feeler is released to perform its feeling function.

Another important object of the invention 45 is to provide a feeler mechanism of the type indicated which shall be simple in construction and efficient in retracting the feeler to a frontward inoperative position when the feeler is moved frontwardly on a detecting beat by a working supply of filling, so that during the inoperative period 50 of the feeler it will not engage the filling.

The invention will best be understood

from the following description and the accompanying drawings of one good, practical form thereof, and will then be definitely pointed out in the claims.

In the drawings:

Fig. 1 is a plan view showing the feeler mechanism embodying the present invention, and sufficient of the loom cooperating parts to enable the invention to be properly 60 understood;

Fig. 2 is a view similar to that of Fig. 1, but showing the feeler in its frontward retracted position;

Fig. 1^a is an enlarged detail more particularly showing the relative inclination of the detent and feeler projection which become engaged when the feeler is moved frontwardly by a working supply of filling 65 in the shuttle on a detecting beat;

Fig. 2^a is a similar view showing the feeler as having been moved laterally by the interengaging surfaces of the detent and feeler projection, the feeler being then in its retracted position, as indicated in Fig. 2;

Fig. 3 is a side view of the feeler mechanism, showing the feeler in its rearward feeling position; and

Fig. 4 is a side perspective view of the feeler mechanism indicated in Fig. 3.

It has not been deemed necessary to illustrate herein the replenishing mechanism and the details of the transmitting means from the feeler to the replenishing mechanism to effect replenishment, because such means are now well understood in the art and the details thereof form no essential part of the present invention.

In the particular feeler mechanism shown as embodying the present invention, the feeler is of the inclined type generally similar to that of the Stimpson Patent No. 1,309,226, July 8, 1919, in which the feeler calls for a change of filling when it is moved in a direction longitudinally of the shuttle 90 or laterally upon substantial exhaustion of the filling, but the advantages of the invention may also be utilized in other forms of feelers.

Also, it has not been deemed necessary 100 herein to illustrate the lay, the shuttle box and the parts associated therewith, because

these features are or may be as usual, but the present drawings show the filling carrier or bobbin in the position it would occupy with relation to the feeler on a detecting beat. Neither has it been deemed necessary to show and describe the details of the means for supporting the feeler upon the shipper stand or other support, because these features are not a necessary part of the present invention.

The feeler stand 1 is mounted on a suitable support, such, for instance, as the shipper stand, or a bracket extending therefrom, as usual, and is secured thereto by means of a bolt 2 which passes through the slot 3 in a flange of the feeler stand, the construction being such that the feeler may be adjusted in proper co-acting relation with the filling carrier or bobbin in the shuttle.

At the rear portion of the feeler stand 1 is mounted a slide 4 capable of lateral movement, and connected with the slide 4 is the transmitter 5 for communicating movement of the slide to the mechanism which controls the replenishing operation. The slide 4 is provided with a slot 6 through which the feeler 7 passes, the slot 6 being somewhat wider than the feeler which passes through it, so that the feeler may partake of a small lateral movement within the dimensions of the slot 6 without moving the slide 4.

The feeler 7 extends frontwardly, and a stem 8 thereon passes through the front bearing or swivel block 9 and between the bearing or block 9 and mounted on the feeler stem is a spring 10 the rear end portion of which bears against a projection of the bridge 11 secured to the feeler, so that the normal tendency of the spring 10 is to impel the feeler rearwardly into its feeling position. The parts so far described are shown as of the same construction and mode of operation as the similar parts in the patent to Stimpson, hereinbefore mentioned, and if desired, the filling engaging end portion of the feeler may be provided with filling engaging teeth.

In accordance with the present invention the feeler is to be held in an inoperative position for periods of time and when in said position the filling engaging end of the feeler is to be in non-contacting relation with the filling on detecting beats until the feeler is periodically released, whereupon the feeler will move to operative position and if it meets a working supply of filling will be again moved to inoperative position out of contacting relation with the filling. Should the filling be substantially exhausted or approached close to substantial exhaustion when the feeler meets the filling on a detecting beat, it will not be moved frontwardly sufficiently far to engage the co-acting mechanism for holding it in inop-

erative position, and thereafter will continue to operate or function until detection of substantial exhaustion, whereupon the feeler will call for a change of filling.

In the present invention, the feeler is provided with a projection which is engaged by a detent when the feeler is moved frontwardly by a working supply of filling on a detecting beat, and the engaging surfaces of the projection and detent are inclined relatively to each other in a direction transversely of the loom, so that as the lay goes back, the feeler will be given a lateral or side movement sufficiently far that thereafter the filling engaging end of the feeler will not meet the filling on a detecting beat. In connection with this characteristic feature of the invention, a stop is provided to limit such side or lateral movement of the feeler to an extent insufficient to effect replenishment of filling.

As shown in the present instance of the invention, the feeler is provided with a projection 12 which has one or more teeth 13 the rear edges of which, at 14, are arranged to engage a detent 15, the engaging surface 16 of which is inclined relatively to the engaging surfaces 14 of the feeler teeth in a direction transversely of the loom, so that the pressure of the feeler spring 10, as the lay goes back, will cause the feeler to partake of a lateral movement from the position indicated in Fig. 1 to that of Fig. 2, wherein the feeler engaging end 17 will be in an inoperative position and not engage the filling on subsequent detecting beats.

In the present instance of the invention, the projection 12 which is carried by the feeler is conveniently formed as part of the bridge 11, although it may be otherwise constructed, and two teeth 13 are shown on the projection, but obviously, any number of teeth desired may be employed.

The detent 15 is formed as a lever, in the present instance, and pivotally mounted at 18 on a bracket 19 which may be adjustably secured by a bolt 20 to the feeler stand.

The detent 15 is normally under the influence of a spring 21 interposed between its front end portion 22 and a seat 23 on the bracket 19, the construction being such that the end 22 of the detent will be normally raised under the yielding action of the spring 21 to cause the inclined detent surface 16 to engage one of the teeth of the projection 12 of the feeler when the latter is moved frontwardly on a detecting beat by a working supply of filling in the shuttle.

The bracket 19 may be adjusted towards and from the front of the loom by means of a thumb screw 24. In the present instance, the thumb screw 24 is rotatably mounted in an opening 24' formed in the bracket 19 and is threaded into the feeler stand, as indi-

cated in Fig. 3. By loosening the bolt 20 the bracket 19 may be adjusted by the thumb screw 24 to position the detent for correct operative relation with the teeth of the 5 feeler.

When a working supply of filling is present in the shuttle, as indicated in Fig. 1, the filling 26 on the filling carrier or bobbin 27 will meet the end of the feeler and 10 move it frontwardly until the front portion of the teeth 13 on the feeler passes under the teeth or holding portion 16 of the detent, and the two inclined surfaces 14 and 16 will take position as indicated in Fig. 1 and Fig. 15 1^a. When the lay retreats and pressure is relieved from the end of the feeler, the spring 10 which acts normally to impel the feeler rearwardly will cause the inclined surfaces 14 and 16 on the feeler projection 20 and detent to effect movement of the feeler laterally about the front bearing or swivel block 9 as a center and the parts will take 25 position as indicated in Fig. 2 and Fig. 2^a with the filling engaging end portion of the 30 feeler frontwardly displaced, or placed in an inoperative position, so that on subsequent detecting beats the end of the feeler will not contact with the filling until, as 35 will presently appear, the feeler is again released by the detent to perform its feeling function.

The amount of lateral movement thus imparted to the feeler 7 by the cooperating inclined surfaces 14 and 16 on the feeler and 40 detent respectively is sufficient to move the feeling end of the feeler frontwardly into its non-contacting relation with the filling, as indicated in Fig. 2, and in order to limit such lateral movement of the feeler to an amount insufficient to call for replenishment of filling a stop is provided.

In the present instance, the detent 15 has projecting frontwardly from the inclined surface 16 a shoulder or flange 28 against 45 which the side of the projection 12 of the feeler will contact when the feeler partakes of its lateral movement under the influence of the two relatively inclined surfaces 14 and 16, as already described. Obviously, the 50 stop for limiting lateral movement of the feeler may be variously devised, but a simple form of stop is conveniently formed on the detent 15 itself, although in some aspects of the invention the stop may be otherwise provided.

When the feeler is moved laterally by the co-acting surfaces 14 and 16 on the feeler and detent, and is arrested by the stop, such lateral movement of the feeler takes place 55 within the slot 6 of the slide 4 and does not impart to the slide movement to effect replenishment of filling.

As hereinbefore stated, the feeler is held in its inoperative position for periods of time and is released from holding engage-

ment with the detent periodically to enable the feeler to perform its feeling function and detect the condition of the filling in the shuttle on a detecting beat. Various means may be employed for tripping the detent 70 from holding engagement with the feeler, and as shown in the present instance, such means comprises a wire 29 which is encased in flexible covering 30, the end of the wire 29 projecting upwardly through a lug 31 75 conveniently formed in the bracket 19 and engaging the under surface of an overlying projection 32 formed on the detent. If desired, the encased wire 29 may be carried through to the take-up mechanism or other 80 convenient moving part of the loom for endwise movement imparted to the wire within its casing from time to time to thereby raise the rear end of the detent and free the feeler for movement to operative position. It has 85 not been deemed necessary to describe the means for imparting endwise movement to the wire 29, because the details of such construction are not part of the present invention. 90

If it be assumed that the feeler is in its rearward feeling position and a working supply of filling is in the adjacent shuttle box on a detecting beat, the feeler will be engaged by the filling and be moved frontwardly thereby to an extent sufficient to cause one of the teeth 13 on the projection 12 to pass under the detent, which may be lifted by the inclined frontward surface of the teeth 13, whereupon the rear end of the detent 15 will be lowered into its operative position again by the spring 21, so that the inclined surfaces 14 and 16 on the feeler and detent respectively will be engaged, as indicated in Fig. 1 and Fig. 1^a. As the lay starts back and the inclined surfaces 14 and 16 are impelled towards each other, their relative inclination will cause the feeler to move laterally from the position of Fig. 1 and Fig. 1^a to that of Fig. 2 and Fig. 2^a, whereupon the rear end portion of the feeler will be moved to an inoperative position and the stop 28 will limit the lateral movement. 100 105 110

The feeler will thus be held in its inoperative position for a period of time or for a number of picks, which may vary, whereupon the wire 29 from its actuating mechanism will cause the rear end of the detent 15 to be raised, thereby freeing the feeler to its rearward movement under the influence of the feeler spring 10. Should the feeler again meet a working supply of filling in the shuttle on the following detecting beat, it will again be moved frontwardly and be engaged by the detent and again moved to its inoperative position. Should however, the filling in the shuttle have approached near to substantial exhaustion, the feeler will not be moved frontwardly sufficiently far on the next detecting beat to be engaged 120 125 130

and locked by the detent but will remain in operative position and call for a change of filling when that in the shuttle has reached a condition of substantial exhaustion.

What is claimed is:

1. In a feeler mechanism for looms, the combination of a feeler, a spring normally impelling the feeler towards its rearward position, a part connected to the feeler and having a detent engaging tooth, a detent for engaging said tooth, the engaging surfaces of said tooth and detent being relatively inclined in a direction transversely of the loom and constructed and arranged to cause the feeler to be moved laterally under the influence of said spring when the detent engaging tooth and detent are engaged as the lay goes back after a detecting beat.
2. In a feeler mechanism for looms, the combination of a feeler, a spring normally impelling the feeler towards its rearward position, a part carried by the feeler and having a detent engaging member, a detent for engaging said member, the engaging surfaces of said member and detent being relatively inclined in a direction transversely of the loom and constructed and arranged to cause the feeler to be moved laterally under the influence of said spring when the detent engaging member and detent are engaged as the lay goes back after a detecting beat, and a stop for limiting such lateral movement of the feeler to an amount insufficient to effect replenishment of filling.
3. In a feeler mechanism for looms, the combination of a feeler, a spring normally acting in a direction to move the feeler towards feeling position, a detent for holding the feeler in frontward or non-feeling position, and interengaging teeth carried by the feeler and detent for holding the feeler in non-feeling position and having their engaging surfaces relatively inclined in a direction transversely of the loom to effect lateral movement of the feeler under the influence of the feeler spring when said surfaces are engaged as the lay goes back.
4. In a feeler mechanism for looms, the combination of a feeler, a spring normally acting in a direction to move the feeler towards feeling position, a detent for holding the feeler in frontward or non-feeling position, interengaging teeth carried by the feeler and detent and having their engaging surfaces relatively inclined in a direction transversely of the loom to effect lateral movement of the feeler under the influence of the feeler spring when said surfaces are engaged as the lay goes back, and a stop for limiting such lateral movement of the feeler to an amount insufficient to effect replenishment of filling.
5. In an intermittent feeler mechanism for looms, the combination of a feeler mounted

to detect substantial exhaustion of the filling on a detecting beat, a detent for holding the feeler in retracted front position, a projection connected to the feeler for engaging the detent, said projection and detent having their engaging surfaces constructed and arranged to cause the feeler to be moved laterally into an inoperative position when the lay goes back and the projection and detent are engaged and a stop for limiting the lateral movement of the feeler by the engaged projection and detent.

70 6. In an intermittent feeler mechanism for looms, the combination of a feeler mounted to detect substantial exhaustion of the filling on a detecting beat, a detent for holding the feeler in retracted front position, a projection connected to the feeler for engaging the detent, said projection and detent having their engaging surfaces constructed and arranged to cause the feeler to be moved laterally into an inoperative position when the lay goes back and the projection and detent are engaged, and a stop for limiting the lateral movement of the feeler by the engaged projection and detent.

75 75 7. In an intermittent feeler mechanism for looms, the combination of a feeler mounted to detect substantial exhaustion of the filling on a detecting beat, a detent having a feeler holding tooth for holding the feeler in retracted front position, a toothed projection connected to the feeler for engaging the holding tooth of the detent, said teeth having their engaging surfaces constructed and arranged to cause the feeler to be moved laterally into an inoperative position when the lay goes back and the teeth are engaged, and means for periodically releasing the feeler from the detent that it may perform its feeling function.

8. In a feeler mechanism for looms, the combination of a feeler mounted to enter the shuttle on a detecting beat in a direction inclined to the longitudinal axis of the shuttle, a spring for normally impelling the feeler rearwardly, a detent for holding the feeler in frontward retracted position, a projection carried by the feeler for engaging the detent when the feeler is moved frontwardly by a working supply of filling, the interengaging surfaces of the projection and detent being relatively inclined to effect lateral movement of the feeler to an inoperative position that it may not injuriously contact with the filling on subsequent detecting beats, a stop carried by the detent to limit the lateral movement of the feeler into its inoperative position, and means for automatically releasing the feeler from the detent from time to time to detect the condition of the filling and effect replenishment when the filling is substantially exhausted.

shuttle on a detecting beat in a direction inclined to the longitudinal axis of the shuttle, a spring for normally impelling the feeler rearwardly, a detent for holding the feeler in frontward retracted position, a projection carried by the feeler for engaging the detent when the feeler is moved frontwardly by a working supply of filling, the interengaging surfaces of the projection and detent being relatively inclined to effect lateral movement of the feeler to an inoperative position that it may not injuriously contact with the filling on subsequent detecting beats, a stop for limiting the lateral movement of the feeler, and means for automatically releasing the feeler from the detent from time to time to detect the condition of the filling and effect

replenishment when the filling is substantially exhausted.

10. A feeler mechanism for looms, comprising, in combination a feeler, a detent for holding the feeler in frontward position, a projection carried by the feeler for engaging the detent when the feeler is moved frontwardly by a working supply of filling, the projection and detent having their engaging portions relatively inclined to move the feeler laterally to an inoperative position, and a stop carried by the detent to limit such lateral movement of the feeler.

In testimony whereof, I have signed my name to this specification.

EDWARD S. STIMPSON.
